CLAIM

The ornamental design for a powered flower trimmer, as shown and described.

DESCRIPTION

FIG. 1 is a front, top and side perspective view of the powered flower trimmer showing my new design, the trimming cord being shown partially extending from the device;

FIG. 2 is a front elevational view thereof;

FIG. 3 is a rear elevational view thereof;

FIG. 4 is a side elevational view thereof;

FIG. 5 is an opposite side elevational view thereof; and,

FIG. 6 is a top plan view thereof, the bottom view being a mirror image of the top view shown in FIG. 6.

FIG. 1.

FIG. 2.

FIG. 3.

FIG. 4.

FIG. 5.

FIG. 6.
